MASSAGE APPARATUS

Filed Feb. 29, 1928

Inventor:

Josef Kazmazýk

UNITED STATES PATENT OFFICE.

JOSEF KAZMAÝK, OF FRIEDRICHSHAFEN, BODENSEE, GERMANY, ASSIGNOR OF ONE-HALF TO WILHELM HASELMEIER, OF STUTTGART, WURTEMBERG, GERMANY.

MASSAGE APPARATUS.

Application filed February 29, 1928, Serial No. 257,978, and in Germany March 10, 1927.

My invention relates to massage apparatus and more especially to apparatus of this kind which are actuated by hand.

The main object of my invention is a better efficiency in the application of such apparatus. For this purpose, according to my invention, the massage element on its working surface is substantially spherically shaped and the connection with its handle 10 is made by a joint which allows for movement in various directions. This joint may be a universal joint of any way of construction, for example a ball joint. I prefer a joint which allows for easy connection and 15 disconnection between the massage element and the handle, so that it will be possible readily to exchange different kinds of massage elements to be used with the same handle.

20 According to my invention the spherical curvature of the working surface of the massage element may be substantially alike all over the surface or it may vary in such manner that the middle portion is rounder 25 than the surrounding outer portions or vice versa. For different portions of the body it may be advisable to change the way of massaging which can easily be effected by exchanging differently shaped massage elements as provided in accordance with my invention.

30 The efficiency of the massage elements will be increased by providing projections on the working surface. These projections can 35 have any desired shape and can be arranged in series or any other manner, as circumstances may afford. I prefer to make the working surface of the massage element and also the projections thereon out of rubber 40 or of a similar elastic material; whereas the core of the element can be metal, wood, hard rubber or any other suitable material.

Having given a general description of my invention I now want to point it out more 45 in detail referring to the drawing which represents an example embodying my invention.

The figure shows the massage element in section whereas the handle thereto is shown 50 in side view.

The surface *a* of the massage element has 55 projections *b* and is stretched over the core *c* to which it is fastened in any suitable way,

for example by means of glue or the like. Core *c* in its middle portion has a cavity 55 adapted to receive ball *d* belonging to handle *f*. An adequately shaped nut *e* is screwed into core *c* so as to secure handle *f* to the massage element.

For certain purposes it may be advisable 60 to have the cavity in the core *c* not exactly in its middle but more or less sideways so that the resistance when massaging varies in the different directions which will cause 65 a difference in the speed of the movements and also in the pressure exerted on the various parts of the body undergoing the massaging treatment at a time.

Of course there will be a certain amount 70 of friction also in the ball joint, for example, which has to be overcome when applying the apparatus.

Under all circumstances the connection 75 between the handle and the massage element has to allow for an ample movement of the element around the fastening point. This is the main feature of my invention. In the example represented these conditions are met by shaping the nut and the part of the handle adjacent to the ball *d* so that the 80 handle is freely movable around the ball joint.

The handle may have any suitable shape. It can be straight and cylindrical like represented in the drawing or it may be curved 85 or made from portions linked together so as to allow for shaping the handle in accordance with the prevailing circumstances or to best suit the operator.

I do not want to be limited to the details 90 described or shown in the drawing, as many variations will occur to those skilled in the art without deviating from the spirit of my invention.

What I claim is:

1. A massage apparatus comprising a 95 massage element having a spherically shaped working surface with projections thereon; a handle; and a universal ball joint connecting said element to said handle, the ball projecting into the interior of the massage element.

2. A massage apparatus comprising a 100 massage element having a spherically shaped working surface with projections thereon; a handle; a universal ball joint connecting 105

said element to said handle; and means for easily connecting and disconnecting said universal joint.

3. A massage apparatus comprising a massage element having a spherically shaped working surface with projections thereon; said working surface being made from re-

silient material, such as rubber; a handle; a ball joint comprising a ball fixed to said handle and adapted to fit into a cavity in 10 said element, and a nut adapted to fit over said ball and to be screwed on to said element.

JOSEF KAZMAZÝK.
